INVENTOR

UNITED STATES PATENT OFFICE.

WILLIAM ROEMER, OF NEWARK, NEW JERSEY.

DESIGN FOR A LOCK-HASP.

SPECIFICATION forming part of Design No. 31,794, dated November 7, 1899.

Application filed October 11, 1899. Serial No. 733,320. Term of patent 14 years.

To all whom it may concern:

Be it known that I, WILLIAM ROEMER, a citizen of the United States, residing at Newark, in the county of Essex and State of New Jersey, have invented and produced a new and original Design for a Lock-Hasp; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a perspective view of a lock-hasp of my novel design, and Fig. 2 is a central longitudinal section of the same.

As shown in the drawings, the leading or

material feature of my design consists of a lock-hasp A, one end of which is approximately disk shape, as at B, and the opposite end approximately quadrangular, as at C, with an open quadrangular center D, as shown more clearly in Fig. 3.

Having thus described my invention, what I claim as new is—

The design for a lock-hasp as herein shown and described.

In testimony that I claim the foregoing I have hereunto set my hand this 4th day of October, 1899.

WILLIAM ROEMER.

Witnesses:

CHARLES H. PELL,
C. B. PITNEY.
